UNITED STATES PATENT OFFICE.

EDWARD B. JACOBSON, OF PITTSFIELD, MASSACHUSETTS, ASSIGNOR TO J AND B MANUFACTURING COMPANY, OF PITTSFIELD, MASSACHUSETTS, A CORPORATION OF MASSACHUSETTS.

IGNITION-TIMER.

1,333,587.

Specification of Letters Patent.

Patented Mar. 9, 1920.

Application filed May 31, 1919. Serial No. 300,914.

To all whom it may concern:

Be it known that I, EDWARD B. JACOBSON, a citizen of the United States, residing at Pittsfield, in the county of Berkshire and State of Massachusetts, have invented certain new and useful Improvements in Ignition-Timers, of which the following is a specification.

The present invention relates to ignition timing apparatus adapted for use in connection with explosive engines, and particularly concerns structural improvements in the contactor carried by the rotary portion.

One object of the invention is the provision of improved means for preventing the usual arcing of the electric current between the contactor and the several contact elements in the casing. A further and more essential object is to extend the period of circuit closure in each ignition circuit prior to the instant of ignition for the purpose of improving the efficiency of the magnetic flux about the core in each of the induction-coil units and thereby producing a spark at the spark-gap of higher voltaic and caloric value.

The foregoing objects I achieve by the provision of a contactor adapted to establish circuit connections in a new or succeeding circuit before interrupting the existing circuit.

In devices of this character it has been the general practice to interrupt and terminate the active ignition circuit before allowing a new circuit to be closed. It may be observed that the instant of ignition in the explosion chamber of the engine is deferred pending a proper duration of circuit closure to enable the magnetic flux in the induction coil to "build up" and attain the requisite strength to produce a spark of sufficient caloric value to effectually ignite the explosive charge, and hence does not usually occur until the contactor in the timing apparatus has traveled over a major portion of the surface of the contact-element. As it is desirable that this "building up" process should be fully developed before the application of the current to ignition, the present invention is designed to close the circuit in each induction unit immediately after ignition occurs in the preceding circuit.

With the foregoing and other objects in view, the present invention consists in the

construction, arrangement, combination and operation of parts, as hereinafter described and shown, and pointed out in the claims.

Referring to the accompanying drawings, Figure 1 is a longitudinal vertical section of an ignition timer embodying the present invention in its preferred form and operatively mounted upon a cam-shaft; Fig. 2, a cross-section of the same on a line intermediate the rotor portion and the face of the housing; Fig. 3, a longitudinal vertical section of the rotor portion mounted as shown in Fig. 1; Fig. 4, a vertical cross-section of the rotor assembly on a plane coincident with the inner face of the outer radial carrier-arm; Fig. 5, a front face view of the contactor carried by the rotor portion; Fig. 6, a side view of the same; Fig. 7, a rear view of the same; and Fig. 8, a detail side elevation of the rivet pin carried at the outer end of the contact-arm for supporting the contactor.

The mechanism herein illustrated is designed for use in connection with a four-cylinder explosive engine having a gear-driven cam-shaft operated by the main engine shaft, but it should be understood, however, that my invention is susceptible of application, with slight modification, to motors having a different number of explosion cylinders, and may be otherwise mounted and driven.

This invention may be adapted to any suitable form of housing or casing, the casing 1 herein illustrated being adjustably mounted on the front of the engine housing 2 and arranged to inclose the front end of a cam-shaft 3, which is preferably geared to the main engine shaft (not shown) and extends through a suitable opening in the wall of the engine housing.

The rear end of the casing 1 is open and seated in a circular recess 4 provided on the face of the engine housing 2, said recess being adapted to prevent eccentric displacement of the casing. Forward displacement of the casing is prevented preferably by a spring clamp 5 removably secured at its rear end to a stud or bolt 6 fixed to the wall of the engine housing 2, and engaging at its opposite end the outer extremity of the reduced forward extension of the front of the casing, which has a central depression to receive a boss 7 provided on the clamp 5.

Axial movement of the casing for regulating the time of ignition is controlled by a lateral arm 8 exteriorly mounted on the casing and provided with a bearing 9 to receive a control-rod (not shown).

Within the casing 1 is an insulation ring 10 provided at regular intervals with arcuate contacts 11, 11, which are embedded on its inner rim and suitably connected to separate terminals 12, 12, etc. arranged on the outside of the casing 1, for connection with the primary circuit of separate induction coils.

Mounted to rotate with the shaft 3 within the casing 1 is a metallic carrier 13 in a form of a sleeve which is normally secured against axial movement on the shaft by a transversely arranged removable pin 14 projecting through a suitable opening 20 in the shaft and extending at one of its ends into a slot 15 provided on the outer rim of the carrier. The pin 14 is secured against end-wise displacement by a cup washer 16 fitted over the outer end of the carrier and inclosing the exposed end of the pin, the reduced outer end 17 of the shaft being projected through the cup washer 16 and suitably threaded to receive a pair of nuts 18, 19, which are employed in conjunction with a flat washer 20, carried on the reduced end of the shaft and engaging the face of the cup washer, to secure the latter in position.

The carrier 13 is laterally provided with a pair of fixed radial arms 21, 21, arranged in spaced parallel relation to each other and pivotally supporting at their outer ends a contact-arm comprising a pair of oppositely arranged plates 22, 22, which are curved in outline and secured at their rear ends to the carrier arms by a transversely arranged pin 23. Said pin 23 has reduced extensions 24, 24, at opposite ends adapted to fit into corresponding openings provided in the plates 22, 22, and are slightly burred at their extremities to prevent lateral displacement of the plates. The contact-arm is reinforced centrally by a transverse spacer-pin 25, which is similar in form and manner of attachment to the pin 23, and is adapted to maintain the relative spacing of the plates 22, 22.

Removably mounted between the front ends of the plates 22, 22, and extending through oppositely arranged transverse openings therein of corresponding size is a removable rivet 26 secured in position against lengthwise displacement at one end by a head 27 exteriorly engaging one of the plates 22, and at the opposite end, which is slotted, by clenching the points 28, 28, so as to overlie the remaining plate 22.

Movably mounted on the rivet 26 between the plates 22, 22, is a contactor 29 having a longitudinally extended body-portion dis-

posed in the plane of the insulation ring 10 and provided with an outer arcuate bearing-face adapted to slidably engage the inner rim of the insulation ring, the rear or inner face of the contactor being provided with a reduced extension 30 adapted to seat movably in the jaw formed by the plates 22, 22, and having a transverse bore 31 to receive the rivet 26 which extends therethrough. The body of the contactor 29 is extensively cut away at its middle to provide a deeply seated transverse channel 32 intermediate the contact ends which equilibrates the combined forces resulting from centrifugal action and the exertion of a torsion spring 33, which is carried upon the pin 23 and operates normally to impel the contact-arm outward, one end of said spring being arranged to bear against the central spacer-pin 25, and the opposite end against the carrier 13 (see Fig. 4). The contactor 29 in cross-section has a uniform dimension at least equal to that of the insulation ring 10, to insure even wear at all points upon the latter and the avoidance of any grooves or ridges which, otherwise resulting, would impair the passage of the electric current. The length of the arc embracing both contact faces of the contactor is designed to somewhat exceed the space between any two adjacent contact-elements, on the insulation ring 10 so that the contactor may establish electrical connection with the succeeding contact-element before entirely leaving the contact-element in whose circuit ignition has last occurred.

The object of thus constructing the contactor so that its extremities will barely overreach the opposing extremities of two adjacent contact-elements is twofold. Primarily it is intended to establish the current in the next firing circuit immediately after ignition has occurred in a given circuit without loss of time involved in the transition of the contactor from one contact-element to another, during which the magnetic flux about the core of the induction-coil may be built up to its maximum efficiency. Secondly, the usual arcing of the current across the gap occurring between the contactor and the receding contact-element, and which has a tendency to injure their respective metals, is avoided, as a new path for the current is established before the old is interrupted.

The inclinations of the faces 34, 35, at the forward and rear ends of the contactor, respectively, are designed to maintain the original length of the arc of contact, said inclinations being at somewhat different angles to compensate for slight changes in the relative positions of the contactor and the contact-arm caused by wear of the contactor. As shown, the outer margins of the plates 22, 22, are cut away at their outer

ends to allow ample space for free pivotal action of the contactor in adjustment with the inner face of the ring 10.

The intersection at an acute angle of the forward face of the contactor with the corresponding contact face provides a suitable cutting edge, which the wear from engagement of these parts keeps in condition, for removing from the surface of the contact-elements

10 11, 11, etc., any adhesions of non-conductive substances. Undue wear of the engaging parts is prevented by the application of a suitable fluid lubricant in accordance with the usual practice, the lubricant being preferably introduced into the front chamber of the casing through a closable inlet 36 provided in its wall.

While the contactor 29 is designed to possess great durability and can be employed until the contact faces are worn well down toward the inner end of the channel 32, it may be renewed when necessary by the removal of the rivet 26 and the substitution of a new contactor.

25 When the rotor assembly is removed for any reason from the cam-shaft 3, the outward swing of the contact arm under the impulse of the spring 33 is limited by the provision of positive stops in the form of 30 arcuate shoulders 37, 37, peripherally arranged on opposite sides of the carrier 18 and adapted to be engaged by inwardly extending feet 38, 38, provided on the inner margin of the plates 22, 22.

35 I claim:

1. In an ignition timer, the combination with a casing and contact-elements mounted in the casing, of a rotor portion mounted to move in the casing and comprising a carrier 40 having a radial extension, an arm pivoted in angular relation on said extension, and having a free end provided with a jaw, spring means for impelling said free end of arm outward, a support mounted in said jaw, 45 and a contact-member pivotally mounted on the support in said jaw and disposed in the plane of the contact-elements in the casing, said contact-member having a longitudinal body-portion arranged in tangential relation to the axis of the rotor portion, and angular extensions provided at opposite ends of the body-portion and extending into position for engagement successively with the contact-elements of the casing.

50 2. In an ignition timer, the combination with a casing and contact-elements mounted in the casing, of a rotor portion mounted to rotate in the casing and including an arm

pivoted in angular relation thereto and having a free end provided with a jaw, spring 60 means for impelling said free end of the arm outward, a contactor pivotally mounted in said jaw and having a pair of contacts arranged in alinement in the direction of movement and extending into position for 65 engagement successively with the contact-elements in the casing, the maximum reach of said contacts being greater than the interval between any two adjacent contact-elements. 70

3. In an ignition timer, a rotor portion including a carrier, an arm pivotally secured to the carrier and having a free end adapted to be moved toward and away from the carrier, spring means operating to move said 75 free end of the carrier arm outward, a contactor pivotally mounted on said free end and having a body portion extended in the direction of its course of travel, and a pair of lateral extensions arranged at opposite 80 ends of the body-portion and extending outward and having arcuate contact faces, the foremost of said lateral extensions having a cutting edge provided on its front end.

4. In an ignition timer, the combination 85 with a casing, an annular insulation member arranged in the casing and having a travel-face, and regularly spaced contact-elements embedded in exposed position on said travel-face, of a rotor portion mounted 90 to rotate in the casing and including a carrier, an arm pivotally secured to the carrier and having a free end adapted to be moved toward and away from the carrier, spring means operating to move said free end of the 95 carrier arm outward, a contactor pivotally mounted on said free end of the carrier arm and having a contact face of predetermined limits for engagement normally with the travel-face of said insulation member and 100 having a body-portion extended in the plane of said insulation member and in angular relation to its own axis, the front and rear ends of the contactor having planar faces arranged at predetermined inclinations to 105 the travel-face of said insulation member and adapted to maintain the original limits of the contact face on the contactor while the body of the contactor is reduced by wear. 110

In testimony whereof I hereunto affix my signature in the presence of two witnesses.

EDWARD B. JACOBSON.
